UNITED STATES PATENT OFFICE.

CARL E. FLATTER, OF ANDERSON, INDIANA.

TRANSMISSION-BAND BRACKET.

Application filed April 16, 1923. Serial No. 632,424.

To all whom it may concern:

Be it known that I, CARL E. FLATTER, a citizen of the United States, residing at Anderson, in the county of Madison and State of Indiana, have invented certain new and useful Improvements in Transmission-Band Brackets; and I do declare the following to be a full, clear, and exact description of the invention, such as will enable others skilled in the art to which it appertains to make and use the same.

This invention relates broadly to improvements on transmission bands, but has more particular reference to an improved detachable bracket therefor.

The principal object of the invention is to generally improve upon brackets of this class by providing one of novel construction which is connected with the band in an extremely unique manner so as to permit it to be quickly attached and detached, whereby to facilitate insertion and removal of the band without requiring removal of the upper section of the transmission housing.

In the accompanying drawings forming a part of this specification and in which like numerals are employed to designate like parts throughout the same:

Figure 1 is a side elevation of a conventional form of a transmission band equipped with a detachable bracket constructed in accordance with this invention.

Figure 2 is a top plan view thereof.

Figure 3 is a top plan view of the bracket removed.

Figure 4 is a longitudinal section taken on the line 4—4 of Figure 2.

In the drawings, the numeral 1 represents a conventional type of transmission band having the usual stationary operating-rod connecting bracket 2 rigidly secured to one of its ends. In carrying out the invention, I strike relatively small and large transverse arched portions 3 and 4 from the opposite end of the band to provide retainers. For the usual stationary bracket on this end of the band, I substitute a detachable bracket 5 which is equipped with the usual spaced upstanding lugs 6 at its outer end and has its body portion 7 curved to conform to and accurately fit against the curved contour of the band. At its outer end, this improved bracket is equipped with a tongue 8 which is adapted to extend into the small

retainer 3. Inward of this end of the bracket, the body portion is cut out as indicated at 9 to provide a second and larger tongue 10 which is designed for engagement with the inner arched retaining portion 4.

In applying the bracket, it is arranged at an angle with respect to the band with the opening 9 substantially over the arched retaining portion 4. Then, the bracket is moved toward the band and manipulated in a manner to simultaneously project the tongues 8 and 10 through the retaining portions 3 and 4 respectively as clearly illustrated in the drawings.

By providing a detachable bracket, it is obvious that when it is desired to remove the band for relining or for other purposes, the detachable bracket can be taken off and the end of the band on which it is located can then be readily and easily drawn between the drums and the housing without requiring the upper section of the latter to be removed as is ordinarily the case.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the invention as claimed may be resorted to if desired.

I claim:

1. In a transmission band, a detachable bracket having a tongue projecting beyond one end and having a portion cut out inward of said end to provide a second tongue.

2. A transmission band having longitudinally spaced arched portions at one of its ends, and a detachable bracket provided with spaced lugs at one end and with a tongue extending beyond the lugs and slidably received in the outer arched portion, the intermediate portion of said bracket being cut out to form a second tongue engaging the remaining arched portion.

In testimony whereof I have hereunto set my hand.

CARL E. FLATTER.
